UNITED STATES PATENT OFFICE.

CHARLES H. PAJEAU, OF EVANSTON, ILLINOIS.

TOY.

1,325,651.

Specification of Letters Patent. Patented Dec. 23, 1919.

Application filed March 31, 1919. Serial No. 286,605.

To all whom it may concern:

Be it known that I, CHARLES HAMILTON PAJEAU, citizen of the United States, residing at Evanston, in the county of Cook and State of Illinois, have invented certain new and useful Improvements in Toys; and I do hereby declare the following to be a full, clear, and exact description of the invention, such as will enable others skilled in the art 10 to which it appertains to make and use the same.

My invention relates to toys consisting of sectional elements connected by flexible members, its general objects being to provide easily manufactured sectional elements 15 for such toys and to provide simple and effective means for assembling the sections and for maintaining them in their proper assembled relation.

More particularly, my invention relates to 20 toy figures composed of perforated sections connected by means of cords, and aims to provide simple means for assembling and maintaining such sections in their desired 25 relation with a small number of cords, and for concealing the knots in the cords. The constituent sections connected by the cords are desirably substantially spherical and my invention particularly lends itself to the assembling of beads or balls into figures simulating human beings or animals. For example,

Figure 1 shows a toy figure of a man embodying my invention and having the cords 30 arranged also for suspending the figure.

Fig. 2 is a longitudinal section through Fig. 1, showing the disposition of the cords connecting the sectional elements.

Fig. 3 is a transverse section through 40 Fig. 1, looking upward from a line just below the juncture of the body with the arms.

Fig. 4 is a view showing the method of assembling the parts of Fig. 1.

Fig. 5 is a perspective view showing two 45 forms of plugs suitable for use as parts of my invention.

Fig. 6 is a perspective view of a figure of a cat constructed according to my invention.

Fig. 7 is a vertical section through an upper body member showing a simplified form 50 of a body section for use according to my invention.

In Figs. 1 to 4 of the drawings, the toy of my invention consists of a series of wooden 55 balls of suitable sizes connected to each other by two strings. The balls comprising

each of the limbs have only a single axial perforation and the end ball on each limb desirably is recessed at its free end to house a knot in the end of the cord upon which 60 the balls comprising the limb are strung. The balls comprising the body or torso have two parallel bores adapted to house relatively spaced cords and to prevent a rotation of the associated parts when the cords 65 are tightly drawn up. The upper or shoulder ball of the body also has a pair of transverse bores leading respectively from the longitudinal bores to side outlets, so as to accommodate the cords on which the arms 70 are strung. For this past named purpose, the shoulder balls might be drilled longitudinally with two bores and transversely with a single bore intercepting these as shown in Fig. 7. However, with this arrangement, it would be exceedingly difficult 75 to fish the cords for the arms transversely into the ball and then vertically in to the head, unless the vertical bores were of such a large diameter as to afford such an undesirable loose assembling of the parts, as to permit a rotation of the upper body member with respect to the head and the lower body member, thereby allowing these parts to swing out of proper alinement. Likewise, 80 even where no transverse bores are involved, as in the case of the lower body member and of the head member, it would be a slow and difficult task to fish the cords through the bores if the latter were of such a size 85 90 as to afford a fairly snug housing for the cords.

To overcome these objections, I desirably provide certain sections of the toy (such as the two body balls and the head ball in 95 the embodiment of Fig. 1) with longitudinal bores of so large a size that doubled cords may easily and quickly be fished through the same, and I then plug these bores partly with plugs or cores which restrict the perforations to bores of the desirable smaller sizes. The cores or plugs used for this purpose may also be used for forcing the cords through the balls in which the plugs are inserted, thus expediting the assembly. For 100 example, in the embodiment of Figs. 1 to 4, I employ only two cords and first string the leg sections upon one cord, knotting both ends of this cord 1 and doubling the cord into a loop as shown in Fig. 4. Next, 105 I slip the doubled portion of the loop of this cord over the end of a plug 2 of such a size

and shape as to wedge in the bore of the lower body member 3 while leaving two opposed channels between its sides and the walls of the said bore, and force this plug 5 upward into its normal position in its body member. In doing this, the plug pushes the looped middle portion of the cord through ahead of it so that this can then be grasped and pulled beyond the top of this lower body 10 portion.

I then pass a second cord 4 through the transverse bore in the upper body member 8 and string upon this cord, at opposite sides of this body member, the balls comprising the two arms, knotting each end of the cord. Next, I slip another plug 5 under the projecting loop of the first cord and force this plug into the longitudinal bore in the upper body member 6, in doing which 15 this plug pushes the loops of both cords ahead of it, so that these can be grasped and pulled farther, after which I slip a third plug 7 under these two loops and push this third plug into the single bore in the head, thereby forcing the loops through the opening at the top of the head. By pulling upward on these loops, I can simultaneously tighten the cords in both the arms and the legs, likewise drawing the body and head 20 members into close consecutive contact with each other, after which I can knot the cords at the top of the head.

To improve the appearance, I desirably make the plug 7 for the head member shorter 25 than the height of the head, so as to afford a recess at the top of the head for housing at least a portion of the resulting knot. Then the projecting loop portions may, if desired, be used for suspending the figure 30 after the manner of Fig. 2.

With the parts thus assembled, and each plug of such a size as to wedge tightly in the bore into which it is driven, I readily obtain the equivalent of twin bores of 35 smaller diameters than those through which the cords could readily be fished, and therefore am able to secure both a speedy assembling and a firm connection of the various parts of the figure to one another. Likewise, 40 by using wooden turnings for all of the sectional elements excepting the plugs, I am able to construct toys of attractive appearance quite inexpensively. For the plugs or cores, I may employ simple dowels either 45 flattened on opposite sides as shown at 2 in Fig. 5, or channeled as shown at 9 in the same figure. In either case, I can readily make the bores so large as to expedite the assembling, while thereafter contracting 50 these bores to the equivalent of perforations through which the cords could not readily be inserted.

However, while I have described my toy as embodied in the figure of a man constructed 55 of spherical sections, I do not wish to be

limited to these or other details of the construction and arrangement here disclosed, as the same might be modified in many ways without departing from the spirit of the appended claims. For example, Fig. 6 70 shows a similarly constructed figure of an animal also employing the principles of my invention.

I claim as my invention:

1. A toy figure comprising perforate head, 75 body and limb members, and flexible elements affording the connections therebetween and all extending through the head and tightened from the top thereof, the said flexible elements extending respectively 80 through the limbs of the figure.

2. A toy figure comprising perforate head, body and limb members, and cords connecting the same; each of the cords extending through two limb members and being knot- 85 tered at the free end of the latter, all of the cords extending through the portion of the body member adjacent to the head, and all of the cords being tightened from the top of the head. 90

3. A toy figure comprising perforate head, body and limb members, and cords connecting the same; each of the cords extending through two limb members and being knot- 95 ed at the free end of the latter, all of the cords extending through the portion of the body member adjacent to the head, and all of the cords being tightened from the top of the head and extended beyond the head to afford means for suspending the figure. 100

4. A toy figure as per claim 2, in which the terminal element of each limb member is recessed to house the knot in the cord extending through the same.

5. A toy figure as per claim 1, in which 105 the head is recessed at its top, and in which the cords are tightened by a knot housed by the said recess.

6. In a toy figure comprising perforate sections connected by cords, plugs respectively disposed in the perforations of the sections between the cords and the walls of the perforations for affording restricted bores in the said sections. 110

7. In a toy comprising sections connected by a cord, a section having a perforation through the same, and a core inserted in the perforation and having a side spaced from the adjacent wall of the perforation to afford a relatively small bore for housing a part of 115 the cord. 120

8. In a toy comprising sections connected by a plurality of cord portions, a section having a perforation therethrough, and a core wedged in the perforation and having a pair of sides spaced from the wall of the perforation to afford restricted passages for the cord portions. 125

9. In a toy comprising sections connected by cords, a section having a pair of inter- 130

secting bores, a cord extending from the mouth of one bore into the latter and out through the other bore, and a core mounted in one of the bores for contracting the latter.

10. In a toy comprising sections connected by cords, a section having a bore of relatively large diameter with respect to the diameter of the cord, and means inserted after the 10 passing of a cord through the said bore for contracting the latter.

11. In a toy figure comprising sections connected by cords, a shoulder section having a transverse bore slightly larger than the cord and having a considerably larger longitudinal perforation, and a plug housed by the said perforation and having sides facing the transverse bore portions and spaced from the adjacent ends of the latter 20 by a distance approximating the diameter of the cord.

12. A toy figure comprising head and body

sections each equipped with a pair of longitudinal bores, one of the body sections also having a transverse bore, plural limb sections each having a single bore therethrough, and a pair of cords forming the entire connection between the said sections, each of the cords being doubled on itself beyond the head; one of the cords having its 30 halves threaded respectively through the two longitudinal bores in the head and body sections and through the bores in the sections comprising a leg section; the other cord having its halves threaded respectively 35 through the two longitudinal bores in the head section, through part of a longitudinal and of a transverse bore in the body section equipped with the latter, and through the sections comprising an arm.

Signed at Evanston, Illinois, March 26th, 1919.

CHARLES H. PAJEAU
